UNITED STATES PATENT OFFICE.

IRA W. MARSHALL, OF PITTSBURGH, PENNSYLVANIA, ASSIGNOR TO BLAW-KNOX COMPANY, OF PITTSBURGH, PENNSYLVANIA, A CORPORATION OF NEW JERSEY.

ADJUSTABLE LEG EXTENSION FOR TOWERS.

Application filed January 17, 1925. Serial No. 3,067.

The present invention relates to structural towers, such as are employed for carrying transmission lines, telegraph and telephone wires, and more particularly to an extension 5 leg for such towers.

Transmission towers are very frequently erected on hillsides where the cost of bringing all four leg foundations to the same height is excessive. By the present invention, 10 I have provided an adjustable extension adapted to be applied to one or more legs of a tower for connecting such legs to the corresponding leg foundations. This leaves it optional with the person making the 15 installation of a hillside tower as to the precise elevation of the tops of the leg foundations, and enables the tower to be erected from standard structural parts, and thus obviates the necessity of having a special 20 design for hillside towers or of going to the great expense in building footings for these towers at elevations considerably above the ground level.

The accompanying sheet of drawings 25 shows in side elevation the lower part of a tower having adjustable leg extensions embodying my invention connecting two of the legs of the tower with the corresponding leg foundations, which, as shown, are in the form 30 of earth anchors.

Referring to the drawings, 2 and 3 represent two of the corner angles or legs of a transmission tower, which will be assumed to be a rectangular tower having the corner 35 angles constituting the legs 90° angles, but which might be, so far as the present invention is concerned, a triangular tower, in which case the corner angles would be 60° angles. The earth anchors, as shown, consist of studs 40 4 and 5 embedded in concrete foundations 6 and 7 which extend to substantially the same depth below the ground line 8, the latter representing a hillside. The upper ends of the studs are at substantially the same height 45 above the ground line, and therefore at different distances below a horizontal plane such as indicated by the chain lines 9 and 10.

I will now describe the adjustable leg extension which constitutes the present invention. Angles 11 and 12 constitute extension 50 members which fit into the corner angles 2 and 3 and may be slid up and down therein, so as to bring their lower end portions at suitable levels for connection with the upper 55 end portions of the studs 4 and 5 to which

they are secured by bolts at the holes 13. The upper end portion of the member 11 is bolted to the lower end portion of the tower leg 2 at the holes 14. The member 11 also has other holes 16, 17, 18, 19 and 20, etc., 60 by means of which it may be bolted to the leg 2 in different positions of extension. The stud 4 will be set at a proper elevation for using one of the above sets of holes. The member 12 will be similarly connected to the 65 leg 3 and stud 5.

An angle member 21 extends across between the legs 2 and 3 and is connected at its opposite ends to the lower ends of said legs. A diagonal bracing angle member 22 is bolted 70 at one end at the hole 23 to the member 11, thus providing a pivotal connection between the end of the diagonal bracing member and the member 11, so that when the member 11 is connected to the leg 2 in different positions 75 of extension, the member 22 can be swung around in the different positions indicated by the chain lines *a*, *b*, *c*, *d* and *e*, etc. In these different positions of the diagonal member 22, its upper end portion is bolted to the 80 member 21 through the holes 24, 25, 26, 27 and 28 in diagonal member 22, and the holes 29, 30, 31, 32 and 33 in the member 21.

The member 22 is also bolted to the diagonal bracing members 34 and 35, and to the 85 vertical member 36 at the hole 37, through the holes 38, 39, 40, 41, 42 and 43 in the member 22. The members 11, 21 and 22 form a truss which is stiffened by the members 34, 35 and 36, which latter members likewise form a 90 truss with the member 21. This arrangement braces the extension member 11 in any of its adjusted positions. The members 21 and 34 may be bolted to the leg 2 and member 11 at the bolt hole 44, and the member 11 may be 95 additionally secured to the leg 2 by bolts at the bolt holes 45. Additional groups of bolt holes 46, 47, 48, 49 and 50, corresponding to the holes 44 and 45, may be provided for the different positions of the member 11. The 100 members 21 and 35 may be similarly secured to the leg 3 and member 12.

A diagonal bracing angle member 51 is bolted to the member 12 and to the members 34, 35 and 36 and serves to brace the member 105 12. The member 51 can assume different positions corresponding to the positions *a*, *b*, *c*, etc. of the member 22, and can be adjustably bolted to the members 34, 35 and 36 through the bolt holes 52, 53, 54, etc. The member 51 110

does not extend to and connect with the member 21, because it is desirable to use structural steel angles for the members 34, 51, etc., and it would not be feasible to fasten the member 51 adjustably to the member 21 in the same manner as the member 22, because the flanges of the angles would prevent such connection.

If each of the four legs of a tower is to have an adjustable extension member secured thereto, the bracing arrangement shown may be applied to all four sides of the tower and will provide the proper bracing in both directions to hold the legs firmly in place. This bracing arrangement may, however, be applied to only one of the tower legs. For example, the extension member 12 and the diagonal bracing member 51 may be omitted altogether, and the stud 5 secured directly to the leg 3, this being the usual manner of connection. In that case, the bracing arrangement shown would be applied to each of the two sides of the tower intersecting at the leg 2 so as to provide for bracing the leg 2 in two directions.

While I have shown a preferred embodiment of my invention, it will be understood that the invention is not limited to the exact details of construction, or to the exact arrangement shown, but that this may be varied within the scope of the appended claim without departing from the spirit of the invention.

I claim:—

A structural tower having a plurality of legs and a leg foundation for each leg, a leg extension between one leg and its foundation and connected to each, a diagonally extending bracing element connected to said leg extension at one of its ends and having its other end connected with a cross girt between the two legs, a vertical member on the cross girt, diagonals extending from each leg adjacent the cross girt to the vertical member, and another diagonal connected with the other leg and with the said vertical member.

In testimony whereof I have hereunto set my hand.

IRA W. MARSHALL.
